DISPLAY RACK

Clarence J. Lydick, Wichita, Kans.

Application March 24, 1949, Serial No. 1,593

Term of patent 3½ years

(Cl. D80—10)

To all whom it may concern:

Be it known that I, Clarence J. Lydick, a citizen of the United States of America, residing at Wichita, Sedgwick County, Kansas, have invented a new, original, and ornamental Design for a Display Rack, of which the following is a specification, reference being made to the accompanying drawing forming a part thereof.

The single figure of the drawing is a perspective view of a display rack showing my new design.

I claim:

The ornamental design for a display rack, substantially as shown.

CLARENCE J. LYDICK.
